[57] CLAIM

The ornamental design of a composite seafood mallet, cracker and knife, as shown and described.

DESCRIPTION

FIG. 1 is a plan view of an assembled combined seafood mallet, cracker and knife showing my new design.

FIG. 2 is a vertical elevation of one side of my design, the opposite side being a mirror image thereof.

FIG. 3 is an end view of my design as seen from the left-hand end of FIGS. 1 and 2.

FIG. 4 is a view of the opposite end of my design from that shown in FIG. 3.

FIG. 5 is a sectional view of my design as seen on the line 5—5 of FIG. 1.

FIG. 6 is a plan view of the mallet part of my composite design.

FIG. 7 is a side elevation of my design of mallet, the opposite side being a mirror image thereof.

FIG. 8 is an end view of the mallet head end of my design.

FIG. 9 is an end view of the opposite end of my design from that shown in FIG. 8.

FIG. 10 is a plan view of the knife part of my composite design.

FIG. 11 is a side elevation of the knife part, the opposite side being a mirror image thereof.

FIG. 12 is an end view of the knife part as seen from the left-hand end of FIGS. 10 and 11.

FIG. 13 is an end view of the knife part of my design opposite that shown in FIG. 12.
